US00D799449S

(12) **United States Design Patent** (10) Patent No.: **US D799,449 S**
(45) Date of Patent: **** Oct. 10, 2017**

(54) **REMOTE CONTROL**

- (71) Applicant: **LG ELECTRONICS INC.**, Seoul (KR)
- (72) Inventors: **Hyunjin Yoon**, Seoul (KR); **Euisseok Lee**, Seoul (KR)
- (73) Assignee: **LG ELECTRONICS INC.**, Seoul (KR)
- (**) Term: **15 Years**
- (21) Appl. No.: **35/501,496**
- (22) Filed: **Mar. 4, 2016**

(80) **Hague Agreement Data**

- Int. Filing Date: **Mar. 4, 2016**
Int. Reg. No.: **DM/089978**
Int. Reg. Date: **Mar. 4, 2016**
Int. Reg. Pub. Date: **Sep. 9, 2016**

(30) **Foreign Application Priority Data**

Sep. 8, 2015 (KR) 30-2015-0045672

- (51) LOC (10) Cl. **14-03**
(52) U.S. Cl. **USPC D14/218**
